(57) CLAIM

I claim the ornamental design for a card holder, as shown and described.

DESCRIPTION

FIG. 1 is an upper perspective view of a card holder showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The portions of the article shown in short broken lines form no part of the claimed design.
